COMBINED DISPLAY CUBE UNIT AND SUPPORT STAND THEREFOR

Marshall C. Schneider, 99 Ripley St.,
Newton Center, Mass. 01432

Filed May 26, 1971, Ser. No. 147,293

Term of patent 14 years

Int. Cl. D6—07

U.S. Cl. D6—235

Fig. 1

Fig. 2

Fig. 3

Fig. 4

FIG. 1 is a perspective view of a combined display cube unit and support stand therefor showing my new design;

FIG. 2 is a perspective view of a modified form thereof;

FIG. 3 is a perspective view of another modified form thereof; and

FIG. 4 is an enlarged cross-sectional view taken substantially on a plane passing through line 4—4 in FIG. 1.

In each figure, the faces of the base and cubes not shown are the same as the faces shown.

I claim:

The ornamental design for a combined display cube unit and support stand therefor, as shown and described.
